DESIGN FOR A COMBINED SLICER AND CORER

Gerald N. Coughlan, East Orange, N. J.

Application December 27, 1938, Serial No. 82,000

Term of patent 7 years

To all whom it may concern:

Be it known that I, Gerald N. Coughlan, a citizen of the Irish Free State, and a resident of East Orange, county of Essex, and State of New Jersey, have invented a new, original, and ornamental Design for a Combined Slicer and Corer, of which the following is a specification, reference being had to the accompanying drawing, forming a part thereof.

Fig. 1 is a top plan view of a combined slicer and corer embodying my design; and

Fig. 2 is a side elevational view of same.

I claim:

The ornamental design for a combined slicer and corer, substantially as shown.

GERALD N. COUGHLAN.
